US0D1005284S

(12) **United States Design Patent** (10) Patent No.: **US D1,005,284 S**
(45) Date of Patent: ** Nov. 21, 2023

(54) **PENDANT FOR ELECTRONIC AUTHENTICATION**

(71) Applicant: **Authentik Systems, LLC**, Stevensville, MD (US)

(72) Inventors: **Richard D. Cira**, Chester, MD (US); **David Airel**, Chester, MD (US); **Michael Megleo**, Palatine, IL (US)

(73) Assignee: **Authentik Systems, LLC**, Stevensville, MD (US)

(**) Term: **15 Years**

(21) Appl. No.: **29/735,457**

(22) Filed: **May 21, 2020**

(51) LOC (14) Cl. **14-02**

(52) U.S. Cl.

USPC **D14/344**

CLAIM

The ornamental design for a pendant for electronic authentication, as shown and described.

DESCRIPTION

FIG. 1 is a front perspective view of a pendant for electronic authentication;

FIG. 2 is a top view thereof;

FIG. 3 is a bottom view thereof;

FIG. 4 is a front view thereof;

FIG. 5 is a back view thereof;

FIG. 6 is a left side view thereof; and,

FIG. 7 is a right side view thereof.

The broken lines shown in FIGS. 1-7 illustrate portions of a pendant for electronic authentication that form no part of the claimed design.

1 Claim, 5 Drawing Sheets
